CLAIM

The ornamental design for a battery powered portable radio,
as shown and described.

DESCRIPTION

FIG. 1 is a top, front, and right side perspective view of a
battery powered portable radio showing our new design;
FIG. 2 is a front elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a rear elevational view thereof.

The broken line showing on FIGS. 1, 2 and 5 is for
illustrative purposes only and forms no part of the claimed
design.
